UNITED STATES PATENT OFFICE.

JESSE YOAKUM, OF BISBEE, ARIZONA TERRITORY.

TOBACCO-PIPE.

No. 892,793.

Specification of Letters Patent.

Patented July 7, 1908.

Application filed March 20, 1908. Serial No. 422,287.

To all whom it may concern:

Be it known that I, JESSE YOAKUM, a citizen of the United States, residing at Bisbee, in the county of Cochise and Territory of 5 Arizona, have invented new and useful Improvements in Tobacco-Pipes, of which the following is a specification.

This invention relates to tobacco pipes, the object of the invention being to provide 10 in connection with the ordinary tobacco or smoking pipe, a combined wind guard and scratcher which, by reason of its double function, greatly facilitates the lighting of a pipe by providing means for igniting the matches 15 and also for shielding or guarding the same from wind currents during the process of igniting the tobacco.

With the above general object in view, the invention consists in the novel construction, 20 combination and arrangement of parts as herein fully described, illustrated and claimed.

In the accompanying drawings:—Figure 1 is a side elevation of a pipe embodying the present invention showing the wind guard folded. Fig. 2 is a similar view showing the 25 wind guard raised to its operative position. Fig. 3 is a plan view showing the guard arranged as shown in Fig. 1.

In the drawings, 1 designates the bowl of 30 the pipe and 2 the stem thereof. These parts may be composed of any suitable material and constructed and arranged in any preferred manner.

In carrying out the present invention I 35 provide a wind guard 3 which is shown in Fig. 3 as substantially semi-circular or semi-cylindrical in cross section as to its base portion, the said guard tapering or contracting in size towards its outer free end 4. In the 40 preferred embodiment of the invention, the larger end portion 5 of the wind guard forms in shape a curvature to the upper portion of the bowl 1 as clearly indicated in Fig. 3 so as to fit closely around the same either in its 45 folded position as shown in Fig. 1 or in its raised position of use as shown in Fig. 2.

The wind guard 3 is pivotally mounted at 6 on the pipe bowl 1. The pivots may consist of fasteners such as screws as shown in 50 Figs. 1 and 2 and are preferably arranged exactly opposite each other and equi-distant from the front and back of the bowl so as to enable the guard to set closely around the bowl either when raised or lowered. The guard

is also provided with small perforations 7 extending through the longer wall thereof and these perforations are preferably formed by punching the guard from the inside outward so as to provide projecting spurs or points which form a roughened match scratching 60 surface.

After filling the pipe with tobacco, the guard is raised to the position shown in Fig. 2. The match is then struck against the perforated and roughened surface and then held 65 over the pipe bowl, behind the wind guard 3, the operator facing the wind. The guard deflects the wind and in that way shields the flame of the match while air percolates through the smaller perforations 7 and dis- 70 ables any tendency toward a vacuum caused by the wind passing rapidly by the sides of the guard and over the top of the same. Without the perforations 7, the wind would tend to produce a vacuum in the upper por- 75 tion of the pipe bowl and within the guard, causing an eddy which would put out the flame. Such tendency toward a vacuum is however dissipated by the air passing in- 80 ward through the small perforations 7 which divide up the air into small portions which of themselves are not sufficient to put out the flame.

In addition to the match-scratch surface of the wind guard, the bowl may be provided 85 with a match-scratch surface extending a suitable distance around the same as shown at 8, which will add to the convenience of the smoker.

Having thus described the invention, what 90 is claimed as new, is:—

The combination with a pipe bowl, of a wind guard substantially cylindrical in cross section and pivotally connected with the bowl so as to extend downward along one 95 side thereof or upward toward the top of the bowl, said wind guard being provided with perforations formed by punching through the guard from the inside, thereby forming an exteriorly roughened match scratching 100 surface, substantially as described.

In testimony whereof I affix my signature in presence of two witnesses.

JESSE YOAKUM.
